MECHANICAL STOKER

Jerome A. Hoffman, Detroit, Mich., assignor to
 Hoffman Combustion Engineering Company,
 Detroit, Mich., a corporation of Michigan

Application May 29, 1934, Serial No. 728,186

15 Claims. (Cl. 110—115)

This invention relates to mechanical stokers.

One object of the invention is to provide an automatic mechanical stoker constructed and arranged to uniformly feed fuel to a furnace, in which, in the present instance, air under pressure is supplied in such a manner as to introduce secondary air over the fire to increase turbulence between the air and furnace gases to assist completion of combustion and to shield and protect the fuel distributing chamber and elements thereof and parts adjacent thereto from intense radiating heat of the furnace.

Another object of the invention resides in the provision of a mechanical stoker having a fuel distributing chamber which is protected from heat by conduction, convection or radiation from the furnace and which may be accomplished by the supply of air under pressure to the furnace to promote combustion and in a plane to shield the fuel delivery chamber and parts therein and adjacent thereto from detrimental heat attack from the furnace.

A still further object of the invention is to provide in a mechanical stoker, a fuel receiving section, a hollow supporting section, an intermediate fuel delivery casing forming a chamber section having communication with said other sections and embodying in the structure an auxiliary casing forming an air chamber associated with the intermediate fuel delivery chamber in such a manner as to tend to cool the fuel delivery chamber, from which auxiliary chamber, air under pressure is discharged to and through the hollow supporting section to the furnace to promote combustion as well as to promote the life of the delivery chamber casing and its mechanism by reason of protecting the same against intense heat from the furnace.

Another object of the invention resides in the provision of an effective, durable and economical mechanical stoker, embodying among other characteristics, means arranged to intercept and support particles of fuel falling by gravity and failing to pass to the furnace under the influence of the fuel delivery means and maintain such intercepted and supported fuel in the path of a stream of air under pressure and force of a character to sweep and carry such intercepted supported fuel to the furnace for consumption therein.

It is further designed to provide a mechanical stoker including a feeding means and means associated with the stoker structure for the supply of air under pressure to the furnace in such a manner as to prevent the extremely fine fuel from being precipitated over the dead plate of the fur-

nace in amounts such as to overheat the dead plate and consequently create heat liable to attack the stoker.

I aim to prolong the life of mechanical stokers by preventing burning out or warping, or distortion of parts of the stoker incident to heat by radiation, convection, or conduction by the use of air under pressure and yet preheating the air to facilitate combustion of fuel as the air under pressure enters the furnace; and, if desired, I may associate with the stoker a water cooled heat absorbing device of suitable character to cooperate with the air supply to assist in protecting the stoker from a detrimental attacking heat from the furnace.

With these and other objects in view, the invention consists in the construction and novel combination and arrangement of parts herein-after fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:—

Fig. 1 is a side elevation of a mechanical stoker embodying the present invention.

Fig. 2 is a front elevation of the mechanical stoker illustrated in Fig. 1.

Fig. 3 is a vertical longitudinal sectional view taken on the line 3—3 of Fig. 2, looking in the direction of the arrows.

Fig. 4 is a horizontal sectional view taken on the line 4—4 of Fig. 1, looking in the direction of the arrows.

Fig. 5 is a view looking at the rear of the auxiliary casing removed from the stoker structure.

Fig. 6 is a plan view of the auxiliary casing removed from the stoker structure.

Fig. 7 is an end elevation of the auxiliary casing.

Fig. 8 is a vertical transverse sectional view on the line 8—8 of Fig. 5.

Fig. 9 is a fragmentary side elevation partly in section of a modified form of the invention.

Fig. 10 is a front view of the heat absorbing device arranged between the furnace and the stoker in the modified form of invention illustrated in Fig. 9.

Referring now more particularly to the accompanying drawings, there is illustrated an automatic mechanical stoker, wherein A indicates generally, a casing on which is mounted a hopper

1, secured thereon by means of a flange 2 and suitable fastenings 3 or in any other suitable manner.

The reference character 4 indicates a fuel feeding means arranged in the upper portion 5 of the casing A and having communication at 5 with the hopper 1. A suitable slidably reciprocating feeding means indicated, generally, by the reference character B is mounted in the fuel feeding section 4 and it may be of any suitable construction and arrangement but as shown it includes a lower portion 6 and a stepped portion 7 which portions 6 and 7 are slidably and connected in spaced relation with the stepped portion 15 7 above the lower portion 6 and with a feed opening 8 between the lower portion 6 and the stepped portion 7 as shown particularly in Fig. 3. This particular character of feeding means B is not claimed herein and more detailed description would seem unnecessary with respect to the same, although it might be noted that the slide member 6 of the feeding means is adapted to slide on a suitable lining member 9 which is replaceable in the event of wear and which in any event may or may not be employed but if employed will serve to protect the supporting means for the slidable feed member 6 against undue wearing away of the respective part of the framework.

20 The feeding section 4 has communication through a throat 10 with a fuel delivering casing including a chamber section 11 composed of the rearward and downwardly curved plate member 12 of the casing A and formed in part on its front by a frame member C including upper and lower horizontal frame members 13 and 14, respectively, and a front curved wall 15 which wall 15 is curved reversely with respect to the curvature of the frame wall part 12. Thus, the upper portion of the fuel delivery chamber is cylindrically curved in cross section. The lower part or bottom of the delivery chamber 11 is formed by an auxiliary casing, indicated generally by the reference character D, which forms a removable and adjustable lip of the fuel delivery chamber 11. The auxiliary casing D is curved transversely and it has an air chamber, indicated generally, by the reference character E, and a shelf 16 is carried by and projects from the rear wall of the air chamber. The shelf 16 may be eliminated if desired.

The auxiliary casing D includes end walls 17 which are substantially segmental in shape and which extend upwardly from the ends of the air chamber E, the upper wall 18 of the air chamber casing forming the lower wall of the fuel delivery chamber and including a transversely curved extension 19 which is adapted to bridge the space between the front wall 20 of the air chamber E and the lower wall 14 of the frame member C and overlaps the front curved wall 15 of said frame member C. The curvature of the wall 18 and the extension 19 is reversed with relation to the curvature of the member 12 and corresponds substantially with the curvature of the wall 15 of the frame member C. The rear of the auxiliary casing D is spaced from the main casing rear member 12, and as thus formed and associated with such parts of the stoker structure there is provided a throat or opening 21 for the discharge of fuel from the fuel delivery chamber 11 into and through the hollow stoker supporting section F as will be hereinafter explained.

The air chamber E includes a substantially vertical rear wall 22 which is provided with a

relatively narrow longitudinal slot 23 with the inner face of the wall 22 beveled or flared forward, as at 24, to provide for a nozzleled effect to project a curtain or blanket of air under pressure from the air chamber E in a manner and for a purpose to be hereinafter explained. The air chamber E and the air discharging slot 23 are of a length commensurate with the width of a fuel feeding opening of a furnace.

The transversely curved auxiliary casing D having the air chamber E and the forward extension wall 19 is removably and adjustably mounted in the enclosing casing A with relation to the upper cylindrically curved portion of the delivery chamber 11. The removable mounting of the auxiliary casing D and its associated parts is for assembly purposes and the adjustment thereof is to provide for raising and lowering the rear portion or lip of the wall 18 of the auxiliary casing D to regulate and control the distance of throw of the fuel into the combustion chamber of a furnace. One way proposed by me for removably and adjustably mounting the auxiliary casing D and the said parts associated therewith resides in the provision of a pair of arms 28, one at each end 25 of the auxiliary casing D. These arms 28 are disposed below the under face of the wall 14 of the frame member C and supported at their outer ends upon nuts 31 at the upper ends of screw bolts 29. The bolts 29 are for the purpose of 30 supporting the auxiliary casing D threaded vertically through suitable brackets 30 on the enclosing casing A, so that by rotating the screw bolts 29 in one direction, the arms 28 of the auxiliary casing are forced upwardly to correspondingly shift the casing in an upward direction, while, upon rotating the screw bolts in the opposite direction, the arms 28 can lower and the casing D can swing downwardly of its own weight plus the tendency thereof to swing downwardly 40 due to the action of the fuel feeding member as hereinafter described. Each arm 28 has a terminal eye 32 at its inner end to receive a bolt 33. The bolts 33 enter the respective screw threaded sockets 34 formed in the bosses 35 on the front 45 face of the aforesaid extension wall 19 of the auxiliary casing D.

By manipulation of the screw bolts 29, the auxiliary casing D and its air chamber E and the extension wall 19 may be adjusted to raise and 50 lower the rear lip portion of the wall 18 of the auxiliary casing D for the purpose of controlling and regulating the height of the lip portion of the wall 18 to effectively control the feed of the fuel to the furnace. For instance, the higher the rear 55 portion of the wall 18, the farther into the furnace the fuel will be projected. Furnaces are so mounted and constructed as to demand such adjustments as to enable effective feed of the fuel to the furnace. Accordingly, by reason of my 60 particular construction of and the mounting of the auxiliary casing D and its associated parts, I am enabled to easily and readily effect the adjustments required and by reason of the upper portion of the wall extension 19 fitting flush with 65 the curved wall 15 of the frame member C there is maintained such a tight fit between the extension wall 19 and said curved wall 15 as to preclude fuel finding its way between said walls.

The outer face of each end member 17 is provided with an arcuate groove 36. These grooves 36 are guided over lugs 37 secured on the inner faces of the side walls 38 of the enclosing casing A whereby in removing the auxiliary casing D from the stoker with respect to the upper sec- 75

tion of the main delivery casing the auxiliary casing D is readily swung to or swung out of operative position according to the condition of the mounting and adjusting means. There may be 5 times when it is desired to stiffen the connection between the auxiliary casing D and the frame member C. To accomplish this purpose, I provide a plate 25 which is preferably of a length substantially equal to the length of the auxiliary 10 chamber D and which projects forwardly from the front face of the wall extension 19. This plate 25 has slots 26 through which bolts 27 pass and enter the wall 14 of the frame member C, effectively stiffening the connection of the auxiliary 15 casing D to the frame member C.

Each end of the air chamber E is provided with a threaded opening 39 of relatively large size for the reception of a pipe 40 for the supply of air under pressure from any suitable source (not 20 shown) for passage into the air chamber E and out of the same through the aforesaid slot 23. It is obvious pipe 40 must either be a flexible conduit or flexibly jointed to permit of adjustment of the casing D. The front wall of the air 25 chamber E may be provided with a screw 41 (Fig. 3) cut off flush and positioned as illustrated for the purpose of providing for rigidity. This screw 41 is fitted in the lug 42 (Fig. 5).

A revolving delivery element indicated, generally, by the character G is mounted in the delivery chamber section 11 to rotate therein to throw or sweep the fuel off of the upper wall 18 of the auxiliary casing D through the throat 21 to and through the opening 43 of the hollow supporting section F into the furnace and over the entire grate area of the furnace.

The revolving delivery element G is mounted on a transverse shaft 44 which is journaled at its ends in water cooled bearings each including 40 a casing 45, a water chamber 46 and a cylindrical bearing portion 47 in which Timken roller or other bearings 48 are arranged between the shaft and the bearing portions 47. Each bearing casing 45 has an annular boss 48^a at its inner end which 45 rests on a seat 49 formed by a recess in the respective end wall 17 of the casing D and through the bosses 48^a and the bearing casings 45 the shaft 44 rotates. Each bearing casing 45 also has an annular portion 45' which fits in an opening 45^a of the respective side wall of the casing A, each casing 45 also having a flange 45^b through the instrumentality of which end bolts 45^c the bearings may be secured to the side walls of the casing A or otherwise mounted as may be desired. The water for cooling the bearing may be supplied from any suitable source by way of a pipe 45^d and discharged by way of a pipe 45^e, as shown in Fig. 1 or in any other suitable manner.

The means for rotating this shaft 44 is immaterial in so far as the present invention is concerned, but the shaft may be provided at one end with a sprocket wheel 50, confined by a lock nut 51, to receive a drive chain (not shown) for driving purposes.

65 A group of spreading blades H is mounted on the shaft 44 to swing, due to rotation of the shaft 44. Each blade H consists of a rigid tapered arm 52 and a blade 53 rigidly connected to the respective arm. The blade portions of the 70 spreading elements are relatively thick and heavy and the blade portions extend lengthwise parallel to the shaft 44 and have their outer faces curved, as at 52' with their fuel striking faces provided with curved flanges 53. The de- 75 scribed shape of the blades H is such as to pro-

mote a sweeping action of these blades over the bottom portion of the delivery chamber 11 so as to uniformly spread the fuel and effectively throw or sweep such fuel out of the chamber through the feed throat 21, as well as forcibly 5 discharge the same rearwardly through the opening 43 of the supporting section F while at the same time spreading the same uniformly over the entire grate area of the furnace.

The group of blades H are arranged in spaced 10 sets of four blades to each set, as may be gathered by reference to Figs. 3 and 4. The blades of each set are swingingly mounted on a transversely disposed pintle 54 which passes through the hubs 55 of the respective blades H and 15 through spacing elements 56 fastened by keys 57 to the shaft 44, as shown particularly in Figs. 3 and 4. The ends 17 of the auxiliary casing D are cut away on the inner faces, as at 58, to accommodate the end spacing elements 56, as 20 shown in Figs. 4 and 8, the end spacing elements fitting close to the inner ends of the aforesaid bearing casings 45. As the shaft 44 rotates, the spacing elements 56 being secured thereto, and the blades H being swingingly mounted on 25 the pintles 54, it is clear that rotation of the shaft 44 effects such action as to effect an outward swing and rotative movement of the blades H which swing at a speed according to the speed of rotation of the shaft 44 and at all times at 30 such speed of rotation as to cause the blades H to effectively act upon the fuel delivered to the delivery chamber 11 to force the fuel from the delivery chamber 11.

The enlarged outer ends of the blades facilitate the centrifugal action thereof and when the shaft 44 is in action it is clear that there is a powerful driving movement given to the blades H as they move around the delivery chamber 11 effecting a positive discharge of fuel from 40 said chamber. It will thus be understood that the blades are not rigidly held to the shaft 44 but that they have swinging connection therewith through the spacing elements 56 and the pintles 54 and that by virtue of this particular 45 mounting of the blades if an obstruction should occur there will be no danger of breakage of the blades or their mountings because of their capability of giving incident to their pivotal mountings. The speed of rotative movement of the 50 blades H ordinarily remains constant with the degree of rotation of the shaft 44 and it will be seen that by virtue of the particular mounting of the blades, they and the shaft 44 and the bearings do not have to be independently adjusted upon adjustment of the auxiliary casing 55 D.

The stoker supporting section F is located in the lower rear portion of the main casing A, and is shown as constituting a chamber, (see particularly Fig. 3) and this chamber is formed by the furnace attaching plate 59, side walls which are rearward, downward extensions of the side walls of the main casing A, a bottom wall 60 integral with said side walls at their lower ends 65 and a door or closure composed of a baffle plate 61 and an outer plate 62 secured together in spaced relation by the spacing elements 63 and bolts 64. The baffle plate 61 has ventilating apertures 65, as shown and the outer plate 62 70 has ventilating openings 66 and the side walls of the section F may have ventilating perforations 66' and it will be understood that the attaching plate 59 is of size depending upon the size of the furnace opening and that this plate 75

59 is secured to the casing A, say for instance, at 61, by welding or otherwise and that it has openings 68 by means of which it may be secured to the front of the furnace over the fire box fuel inlet opening.

10 The door 61—62 is preferably hingedly mounted by means of a suitable pintle 69 and provided with any common form of latch 70. By virtue of this door 61—62 access is readily had to the 10 interior of the section F for cleaning or other purposes.

15 The stoker described is relatively small and compact with the result that the supporting section F is relatively narrow but in the event that the fuel delivery mechanism should fail to throw or feed all of the fuel through the opening 43 of the supporting section, that is to say, if some of the particles of fuel should fall by gravity as it passes through the throat 21 on the way to the 20 opening 43, such particles falling by gravity would ordinarily go to the bottom of the hollow supporting section F. To prevent this and to conserve fuel and to insure practically all of the fuel discharged from the delivery chamber 11 to 25 go to the furnace, I provide the aforesaid shelf 16 which intercepts and supports temporarily at least such particles of fuel as fall by gravity between the throat 21 of the delivery chamber 11 and the opening 43. This shelf 16 may be provided with end plates 71 formed therewith or welded thereto and the shelf 16 and its ends 71 project from the rear wall of the air chamber E and are preferably welded to the rear wall of the air chamber E with the shelf 16 slightly below the 30 air discharge nozzle 23—24 of the air chamber E so that the air under pressure issuing through the air nozzle 23—24 will effectively sweep the shelf 16 and carry particles of fuel thereon through the opening 43 of the supporting section 35 F into the furnace.

40 The air under pressure issuing from the air chamber E is in the form of a curtain or blanket and of a width substantially the width of the opening 43 of the hollow supporting section F 45 and of the fuel receiving opening leading into the furnace, to introduce secondary air over the fire to increase turbulence between the air and furnace gases, thus assisting completion of combustion. This curtain or blast of air spreads the extremely fine coal over the burning fuel on the grate of the furnace, preventing the fine fuel 50 from being precipitated over the dead plate of the furnace in amounts that would have a bad effect, due to overheating the dead plate and consequently the stoker parts. This air under pressure protects and shields the fuel delivery chamber 11 and the blades from the intensity of the heat of the furnace, thereby preserving the life of the chamber 11 and the parts associated 55 therewith and parts adjacent thereto. Of course there is some heat applied to the chamber 11 and the blades H and parts in close proximity thereto but the curtain or blanket of air modifies the heat to such an extent as to prevent distortion 60 of the front portion of the bottom of the delivery chamber 11 as well as preventing burning out of parts and yet preheats the air of the air chamber E to facilitate combustion of fuel as the air under pressure enters the furnace.

65 70 The curtain or blanket of air has a tendency to prevent noxious gases from leaving the furnace under a balanced draft condition and working back into the stoker and out therethrough to the building in which the furnace is located.

75 It will now be understood since the fuel receiv-

ing section 4 receives fuel from the hopper 1, the reciprocation of the reciprocating means 6—7 brings about feed of the fuel in regulated quantities through the throat 10 to the delivery chamber 11. From chamber 11 the fuel is discharged in regulated uniform quantities through the supporting section F to the furnace and while such a structure, broadly speaking, may not in itself be new, the invention concerned in the present case results in a more effective utilization of such elements by reason of the new features herein described in connection with the fuel delivery chamber 11 and the auxiliary casing containing the air chamber associated therewith as well as the means for intercepting fuel ordinarily precipitated on the dead plate and not on the effective grate area of the furnace.

10 It would seem unnecessary to describe the manner in which the reciprocating feeding means 6—7 is operated as this feeding means forms no 20 part of the present invention. Suffice it to say that the feeding means and the revolving spreader mechanism are operated in timed relation in a manner as may be common in mechanical stokers of the present character.

25 In another embodiment of the invention and with the thought in mind to further protect the stoker from attack by heat radiating from the furnace, and as illustrated in Figs. 9 and 10, I may interpose a water cooled heat absorbing device 72 between the furnace shown in part at 73 and the stoker comprising a frame including front and rear plates 74 and 75 which are maintained in spaced relation by inner and outer sets of spaced metal strips 76 and 77, respectively, 30 which are welded to or otherwise secured to the inner faces of the plates 74 and 75 in a manner to provide water tight joints and to provide a water channel 78 having a water inlet 79 and a water outlet 80. Bosses 81 and 82 are welded or 35 otherwise secured to the front plate 74 and have screw threaded openings which align with the inlet and outlet openings 79 and 80, respectively, and in which screw openings of said bosses pipes (not shown) may be secured to supply water 40 under pressure to the channel 78 for continuous circulation through the channel. The assembled plates have an opening 83 centrally thereof and this opening is adapted to align with the discharge opening 84 in the supporting section 85 of 45 the stoker and with the fire box or combustion chamber fuel receiving opening 86 of the furnace.

50 The heat absorbing device frame may be other than the rectangular shape shown as may also be the central opening 83. The assembled frame of the water cooled heat absorbing device 72 is preferably provided with open ended sleeves or the like 87 welded to the plates 74 and 75, as indicated at 88 and open outwardly through said plates to provide holes to receive bolts or the like 89 adapted to be passed through holes 90 in the wall 91 of the supporting section of the stoker and into the front wall of the furnace as shown in Fig. 9. This type of heat absorbing device is more specifically described in a co-pending application filed by me on the 29th day of May, 1934 Serial Number 728,184 and is not claimed herein except as to combination thereof with other elements. The heat absorbing device may be positioned and held in place between the stoker and the furnace in any suitable manner. As cool water continuously enters the device at the inlet point thereof and by the partition 92 in the water channel is forced to circulate upwardly and around the channel to the outlet point of the de- 55 60 65 70 75 80 85 90 95

vice, heat radiating from the furnace is absorbed by the water in the water channel and carried away from the stoker, protecting the latter from destructive radiating heat attack from the furnace.

5. What is claimed is:—

1. A mechanical stoker including fuel receiving means and a fuel delivery means comprising a main casing including an upper cylindrically curved portion and a lower transversely curved auxiliary casing cooperating with said cylindrically curved portion to form a fuel delivery chamber, a rotary fuel feeding member therein, said auxiliary casing containing an air chamber, the upper wall of the auxiliary casing constituting the lower wall of said main casing, the rear wall of said auxiliary casing being spaced from the rear wall of the upper cylindrically curved portion of said main casing to provide a fuel delivery opening leading from said fuel delivery chamber, the auxiliary air chamber casing having an air discharge opening at the rear thereof below said fuel delivery opening.

2. A mechanical stoker including fuel receiving means and a fuel delivery means comprising a main casing including an upper cylindrically curved portion and a lower transversely curved auxiliary casing cooperating with said cylindrically curved portion to form a fuel delivery chamber, a rotary fuel feeding member therein, said auxiliary casing containing an air chamber below the fuel delivery chamber of an area extending under a substantial area of the lower portion of the fuel delivery chamber, the upper wall of the auxiliary casing constituting a substantial part of the lower wall portion of said main casing, the rear wall of said auxiliary casing being spaced from the rear wall of the upper cylindrically curved portion of said main casing to provide a fuel delivery opening leading from said fuel delivery chamber, the auxiliary air chamber casing having an air discharge opening at the rear thereof below said fuel delivery opening and extending substantially throughout the length of the auxiliary casing.

3. A mechanical stoker including fuel receiving means and a fuel delivery means comprising a main casing including an upper cylindrically curved portion and a lower transversely curved auxiliary casing cooperating with said cylindrically curved portion to form a fuel delivery chamber, a rotary fuel feeding member therein, said auxiliary casing containing an air chamber, the upper wall of the auxiliary casing constituting the lower wall of said main casing, the rear wall of said auxiliary casing being spaced from the rear wall of the upper cylindrically curved portion of said main casing to provide a fuel delivery opening leading from said fuel delivery chamber, the auxiliary air chamber casing having an air discharge opening at the rear thereof below said fuel delivery opening, and means for supplying air under pressure to said air chamber for passage through the latter to cool the lower wall portion of the main casing.

4. A mechanical stoker including fuel receiving means and a fuel delivery means comprising a main casing including an upper cylindrically curved portion and a lower transversely curved auxiliary casing containing an air chamber cooperating with said cylindrically curved portion to form a fuel delivery chamber, a rotary fuel feeding member therein, the upper wall of said auxiliary casing constituting the lower wall portion of the main casing, said upper wall of the aux-

iliary casing including a transversely curved extension extending forwardly and upwardly into the upper portion of the cylindrically curved portion of the main casing and overlapping the front wall of the latter, the rear wall of said auxiliary casing being spaced from the rear wall of the upper cylindrically curved portion of the main casing to provide a fuel delivery opening leading from said fuel delivery chamber, the auxiliary air chamber casing having an air discharge opening in the rear wall thereof below said fuel delivery opening.

5. A mechanical stoker comprising an enclosing casing having fuel receiving means and including sides having inwardly-directed oppositely-disposed lugs, a fuel delivery casing including an upper cylindrically curved portion, and a lower transversely curved auxiliary casing cooperating with the upper cylindrically curved portion to form a fuel delivery chamber, a rotary fuel feeding member therein, said auxiliary casing having upper and lower spaced apart walls forming an air chamber therebetween having an air inlet and outlet, the said outlet being open through the rear wall of the said casing, the upper wall of the auxiliary casing constituting the lower wall portion of said fuel delivery chamber, said upper wall of the auxiliary casing having a transversely curved extension extending forwardly and upwardly into the upper portion of the cylindrically curved portion of the fuel delivery chamber in engagement with the inner face of the upper front wall of the latter, the rear wall of said auxiliary casing being spaced from the rear wall of the upper cylindrically curved portion of the fuel delivery chamber forming a rear delivery opening from the delivery chamber through which fuel is discharged by said fuel feeding member, the ends of the auxiliary casing extending above the upper wall of the auxiliary casing within the sides of said enclosing casing and having curved grooves on their outer faces which slidably embrace the aforesaid lugs on the inner faces of the sides of the enclosing casing as the auxiliary casing is positioned in the enclosing casing or removed therefrom, and means for securing the auxiliary casing in operative position in the enclosing casing and in cooperative relation with the said cylindrically curved portion of the delivery chamber casing.

6. A mechanical stoker comprising an enclosing casing having fuel receiving means and including sides, a fuel delivery casing including an upper cylindrically curved portion, and a lower transversely curved auxiliary casing cooperating with the upper cylindrically curved portion to form a fuel delivery chamber, a rotary fuel feeding member therein, said auxiliary casing having upper and lower spaced apart walls forming an air chamber therebetween having an air inlet and outlet, the said outlet being open through the rear wall of the said casing, the upper wall of the auxiliary casing constituting the lower wall portion of said fuel delivery chamber, said upper wall of the auxiliary casing having a transversely curved extension extending forwardly and upwardly into the upper portion of the cylindrically curved portion of the fuel delivery chamber in engagement with the inner face of the upper front wall of the latter, the rear wall of said auxiliary casing being spaced from the rear wall of the upper cylindrically curved portion of the fuel delivery chamber forming a rear delivery opening from the delivery chamber through which fuel is discharged by said fuel feeding member, cooperative connecting means between the ends

of the auxiliary casing and the sides of the enclosing casing for guiding the auxiliary casing into and out of operative position with relation to the upper cylindrically curved portion of the 5 delivery chamber casing, and means for adjustably fastening the auxiliary casing in operative position with relation to the upper cylindrically curved portion of the delivery chamber casing.

7. A mechanical stoker including fuel receiving 10 means and a fuel delivery means comprising a casing including an upper cylindrically curved portion and a lower transversely curved auxiliary casing cooperating with the upper cylindrically curved portion to form a fuel delivery chamber, 15 a rotary fuel feeding member in said chamber, said auxiliary casing containing an air chamber, the upper wall of which constitutes the lower wall of said fuel delivery chamber, the air chamber having an air inlet and a narrow air outlet of a 20 length substantially the length of the air chamber, and means whereby to supply air under pressure to the air chamber and force a curtain or a blanket of air through said air discharge opening.

8. In a mechanical stoker, a casing having fuel 25 receiving means and including sides and a fuel delivery chamber having a fuel outlet composed in part of an internal substantially segmental-shaped combined apron and air chamber including end portions and upper and lower walls forming 30 between them an air chamber, the upper wall of the combined apron and air chamber constituting the lower wall of the delivery chamber, said air chamber having a discharge outlet, the sides of the casing having oppositely disposed 35 bearing openings therein and the end portions of the substantially segmental-shaped combined apron and air chamber having oppositely disposed openings of smaller diameter than said bearing openings and aligning therewith, water-40 cooled bearings each including a water-jacketed casing having its inner end mounted in said side bearing openings and having its inner end reduced in diameter and fitted in the respective opening of said end portions of the substantially 45 segmental-shaped combined apron and air chamber, a driven shaft extending transversely of the casing adjacent to the combined apron and air chamber and having its ends journaled in the respective water-cooled bearings, a fuel feeding 50 member on said shaft for discharging fuel through said fuel outlet, means for circulating water through said water-cooled bearings, and means for supplying air under pressure to said air chamber for discharge under pressure through the 55 discharge outlet of the latter.

9. A mechanical stoker including fuel receiving 60 means and a fuel delivery means comprising a main casing including an upper cylindrically curved portion and a lower transversely curved auxiliary casing cooperating with said cylindrically curved portion to form a fuel delivery chamber, a rotary fuel feeding member therein, said auxiliary casing containing an air chamber, the upper wall of which constitutes the lower wall 65 of said main casing, means for adjustably mounting the lower transversely curved auxiliary casing in position with relation to the upper cylindrically curved portion of the main casing, means for stiffening the contacting parts of the auxiliary casing and the upper cylindrically curved portion of the main casing after an adjustment 70 has been effected, the air chamber having a discharge outlet and also having an air inlet whereby air may be supplied to the air chamber to cool 75 the lower transversely curved auxiliary casing

and become preheated for discharge through the discharge outlet of the air chamber.

10. A delivering mechanism for a stoker including a casing having a fuel inlet and a fuel outlet, means in said casing for distributing and discharging fuel through said outlet, said casing including a lower portion having a discharge shelf and a chamber for the passage of cooling air through the same to cool the delivering mechanism, said chamber having a discharge opening 10 above the shelf, and said lower portion of the casing being bodily adjustable to vary the inclination of the said shelf and the discharging air stream.

11. A delivering mechanism for a stoker including a casing having a fuel inlet and a fuel outlet, means in said casing for distributing and discharging fuel through said outlet, said casing including a lower adjustable portion having a chamber for the passage of air therethrough under pressure to cool said lower adjustable portion, said lower adjustable portion having a discharge shelf and an air outlet from said chamber above said shelf, and means for adjusting said lower casing portion and holding the same 25 in adjusted position.

12. A delivering mechanism for a stoker including a casing having a fuel inlet and a fuel outlet, means in said casing for distributing and discharging fuel through said fuel outlet, said casing 30 having a lower adjustable portion forming at its rear the lower edge of the fuel outlet and having a chamber provided with an air inlet for the circulation of air to cool the same, said chamber having a rear outlet adjacent to and below the 35 fuel outlet for the discharge of a stream of air with the discharging fuel, and means to adjust the said lower portion of the delivery casing to thus vary the inclination of the discharging air stream.

13. The combination with a furnace having a fuel receiving opening, of a stoker comprising a fuel receiving and distributing mechanism including a casing and a distributing member therein, the casing having an inlet and also having an 45 outlet at the rear end thereof, said outlet being arranged adjacent the fuel receiving opening of the furnace and cooperating therewith to provide a fuel delivery passage between the rear end of the stoker and the furnace, said casing having a 50 lower hollow portion forming an air chamber at the lower portion thereof to receive air under pressure, the air chamber having a relatively long opening in the rear thereof for the supply of a curtain of air under pressure from said air chamber through said relatively long outlet opening 55 thereof to the furnace through said passage at the fuel receiving opening of the furnace and the outlet opening of said casing to assist in the distribution of the fuel and to assist combustion of 60 fuel in the furnace and to protect said casing from detrimental attacking intense heat from the furnace, and a water-cooled heat absorbing device arranged between the furnace fuel receiving opening and the rear outlet of the fuel distributing 65 casing and having an opening aligned with the discharge outlet of said casing and the fuel receiving opening of the furnace to cooperate with the said curtain of air to assist in protecting the stoker casing from attack by the intensity of the 70 heat from the furnace.

14. The combination with a mechanical stoker and a furnace provided with a fuel receiving opening, of a delivery mechanism associated with the stoker including a casing having a fuel inlet 75

and a fuel outlet, an impeller mechanism in said casing for distributing and discharging fuel from said casing through said fuel outlet into the furnace, said casing having a lower portion forming 5 at its rear the lower edge of the fuel outlet and having a chamber under the impeller mechanism provided with an air inlet for the reception of air under pressure to cool the casing beneath the impeller mechanism, said lower portion of the casing 10 being adjustable to vary the inclination of the said lower edge of the fuel outlet, said chamber having a relatively long rear outlet adjacent to and below said fuel outlet for the discharge of a curtain of air under pressure from said chamber of a 15 width substantially the same as the width of the furnace fuel receiving opening simultaneously with the supply of fuel to the furnace to spread the fuel over the burning fuel in the furnace and to assist combustion in the furnace and to shield 20 the impeller mechanism casing and the interior thereof from the intense heat of the furnace by modification of the heated products of the furnace issuing from the fuel opening of the furnace toward the said casing.

25 15. The combination with a furnace having a fuel receiving opening, of a stoker provided with a fuel receiving and distributing mechanism in-

cluding a casing having a fuel outlet at the rear thereof coinciding with the fuel receiving opening of the furnace for the passage of fuel from the fuel receiving and distributing mechanism casing into the furnace, said casing carrying an air 5 chamber at the lower portion thereof to receive air under pressure to cool the interior of said casing and having an outlet in the rear wall of said chamber extending across the fuel receiving opening of the furnace to supply a curtain of air 10 to the furnace under pressure from the air chamber through the outlet of the latter and through said fuel receiving opening, and a water-cooled heat absorbing device arranged between the front of the furnace and the rear of the stoker and 15 having an opening aligned with the outlet opening of said fuel receiving and distributing casing and the fuel receiving opening of the furnace and through which said curtain of air under pressure passes, the curtain of air entering the furnace 20 assisting combustion and also cooperating with said air chamber to protect the interior of the fuel receiving and distributing chamber and parts adjacent thereto from attack by the intense heat of the furnace.
